UNITED STATES PATENT OFFICE.

CHARLES J. RATEIKE, OF CHICAGO, ILLINOIS, ASSIGNOR TO ANSON MARK AND CLAYTON MARK, COPARTNERS DOING BUSINESS AS MARK MANUFACTURING COMPANY, OF CHICAGO, ILLINOIS.

PIPE-BEND.

1,232,973.

Specification of Letters Patent. Patented July 10, 1917.

Application filed March 18, 1915. Serial No. 15,290.

To all whom it may concern:

Be it known that I, CHARLES J. RATEIKE, a citizen of the United States, residing at Chicago, Cook county, Illinois, have invented new and useful Improvements in Pipe-Bends, of which the following is a specification, reference being had to the accompanying drawings, in which—

Figure 1 is an elevation of a plate blank, 10 of a character suitable for forming into a pipe bend; Figs. 2, 3 and 4 are elevations showing successive steps in the reduction and elongation of a blank or shell, preliminary to shaping it into the desired form; 15 Fig. 5 shows the mechanism and manner of forming the shell or blank into a bend or elbow; Fig. 6 shows the bend or elbow after it has been operated upon by the mechanism shown in Fig. 5, and Fig. 7 shows a formed 20 bend after its closed end has been squared and preliminary to aperturing it.

My invention relates to pipe bends or elbows, and consists in the formation of bends or elbows from plate blanks or cup-shaped shells. Fittings constructed in accordance with my invention are of uniform 25 strength and thickness, and are extremely cheap and easy to make. Various features of my invention will also be found to be 30 hereinafter described and claimed.

Referring to the drawings, the plate shown in Fig. 1 is normally reduced to the shell-like form shown in Fig. 2 by a drawing operation, and may then be reduced by 35 further drawing operations to the forms shown in Figs. 3 and 4. When it has been reduced so that its open end 2 is of substantially the diameter of one of the ends of the finished bend, it is then placed upon the 40 mandrel 4 of the block 5, so that its end 2 is supported, as is shown in Fig. 5. The block 5 has a curved upper face 6, which corresponds to the curvature which it is desired to have the longer side of the completed 45 bend assume. The die 7 then descends, and its curved face forms the blank into the shape shown in the dotted lines in Fig. 5, and in full lines in Fig. 6. The end 3 of

the blank may then be squared, as is shown in Fig. 7, after which the elbow may be 50 apertured and threaded.

I have found, in carrying out my invention, that the metal does not draw away from the end 2, but remains true at that end, and the metal at the end 3 can readily 55 be trued or squared and then apertured or threaded. It is obvious that completing the form of the blank before aperturing its closed end enables the metal to be worked with much greater freedom than would be 60 the case if the end was apertured before the shaping operation was completed. The number of operations necessary to form elbows has been greatly decreased in carrying 65 out my invention, and the resulting product is much cheaper than heretofore.

The terms and expressions which I have employed herein are used as terms of description and not of limitation, and I have no intention in the use of such terms and 70 expressions of excluding any equivalent for the features shown and described, but recognize that various modifications are possible within the scope of the invention claimed.

What I claim is:

1. The process of making pipe bends which consists in shaping a shell of cup-shaped form by supporting its bottom end and applying compression to the exterior of the top and bottom of said shell while the 80 interior of the top end is unsupported, and causing one of its sides to bulge outwardly in a direction transverse to the longitudinal axis of the shell and thereby forming a fitting of elbow shape, and then aperturing 85 the bulged-out portion.

2. The process of making a pipe bend which consists in taking a plate, forming it into a cup-shaped blank having substantially the diameter of one end of the completed elbow, then swaging the exterior of the blank while the interior of the closed end is unsupported and causing one of its ends to bulge in a direction transverse to the longitudinal axis of the blank, and aperturing 95 the bulged side.

3. The process of making pipe bends, which consists in forming a plate blank into a shell having a closed end, then supporting its open end and applying compression to the exterior of its closed end while the interior of the closed end is unsupported, and thereby causing a side of the shell to bulge

laterally, then truing the end of the bulged portion and aperturing it.

CHARLES J. RATEIKE.
